UNITED STATES PATENT OFFICE.

A. JESSE LANDON, OF JAMESTOWN, NEW YORK.

SPRING BED-BOTTOM.

SPECIFICATION forming part of Letters Patent No. 256,335, dated April 11, 1882.

Application filed August 1, 1881. (No model.)

To all whom it may concern:

Be it known that I, A. JESSE LANDON, a citizen of the United States, residing at Jamestown, in the county of Chautauqua and State 5 of New York, have invented certain new and useful Improvements in Spring Bed-Bottoms; and I do hereby declare the following to be a full, clear, and exact description of the invention, such as will enable others skilled in the 10 art to which it appertains to make and use the same, reference being had to the accompanying drawings, and to letters or figures or reference marked thereon, which form a part of this specification.

15 The object of my invention is to make a cheap and efficient spring bed-bottom, and one less liable to get out of order than others; and it consists in an improved link for holding the springs in proper position and a brace for 20 holding the side rail, in the manner as herein-after more fully set forth.

In the accompanying drawings, Figure 1 shows a section of a spring bed-bottom with 25 my improvements attached; Fig. 2, a side elevation of link; Fig. 3, a plan view of the link; Fig. 4, a plan view of brace.

In that class of spring bed-bottoms having the large part of the spring-coil upward and held in position by a link passing from one 30 coil to the other, the common way of making the link has been to wrap a wire around a suitably-shaped iron a large number of times, and then cut these coils and hook them from one spring to the other with the opening down; 35 but these links in shipping and every day use easily get turned so as to bring the opening up, and then are liable to tear and injure the mattress. To overcome this turning some have made a loop in one end of the link and

run the coil-spring through this before closing 40 the spring; but this is objectionable not only in putting up but when desired to change the width of bed.

My improvement overcomes these difficulties. I make my link D with a loop, E, near one 45 end, as shown in Fig. 2, and have the loop just low enough so the spring can be forced by this loop to the end of the link, and the loop prevents the link from turning end for end when in use, and can be put on and taken off at will. 50

My improvement consists, also, in the spring-brace B, as shown in Fig. 4, for holding the side rail, x, in position. This brace I make of steel having one end turned so as to readily attach to the cross-bar C, and the other end 55 given two short turns nearly right angle, and the end left so then it will pass into a hole in the side rail and come against this shoulder, as shown at m, Fig. 4, thus preventing the side rail from coming in when weight is put on the 60 bed, and can be readily detached in shipping.

I claim—

1. In combination with spring bed-bottoms, the connecting-link having a loop near one end of suitable size to prevent the link from changing ends on the coil, substantially as shown and described, and for the purpose set forth. 65

2. In combination with spring bed-bottoms having cross-bar and side rail, substantially as shown, the spring-brace B, having turns l 70 and m at end, as shown and described, and for the purpose set forth.

In testimony whereof I affix my signature in presence of two witnesses.

A. JESSE LANDON.
